UNITED STATES PATENT OFFICE.

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD OF UNITING PARTS OF BOOTS AND SHOES.

Application filed January 7, 1920, Serial No. 468,305. Renewed May 10, 1921.

This invention relates to methods of uniting parts made of leather or similar materials and is herein set forth with special reference to its practice in the formation of 5 seams for uniting together parts made of heavy leather such, for example, as that employed in the manufacture of moccasins, larrigans, and the like.

In an article of footwear of this type the 10 sole and sides are commonly made with a single piece of leather and the toe piece is secured to the upturned margin of the sides about the toe portion to form an enclosure for the toe portion of the foot, and generally 15 a top piece is sewed to the margin of the sides about the rear portion to form a covering for the instep and ankle of the foot.

Hitherto the formation of the seam between the sides and the toe and top pieces 20 by machine has presented such difficulties that the use of machines for this work has been very restricted. An object of this invention is to provide a method by which the formation of this seam by a machine is not 25 only practicable but easy and by which not only a great deal of time may be saved, but results equal or superior to those obtained by the previously extensively practiced hand work may be obtained.

30 It is to be understood, however, that although the present method is preeminently adapted for sewing parts of moccasins, it is not limited to that use but may be employed in making other seams in other articles.

35 As herein exemplified illustratively, the method of the present invention may advantageously be practiced by first trimming the edges of the parts to be joined even and forming a groove at a predetermined short 40 distance from the trimmed edge, preferably on the inner or flesh side of the margin of each piece to be joined. Hereafter the term "margin" will refer to the portion between the groove and the edge when a groove is 45 employed, the portion inside the groove or beyond the line at which the margins are turned outwardly being called the body portion. When the grooves are used the margins are placed together with their edges

flush and, of course, with the grooves parallel and opposite to each other, preferably on the inside. The margins may then be temporarily secured together, for instance, by staples of fine wire. This enables the parts, if a shoe is being made, to be placed 55 upon a last for subsequent operations. The placing of the parts upon a last disposes the body portions at more or less of an angle to each other varying at different portions of the shoe, for instance, at the toe the angle 60 between the toe piece and the sides is substantially a right angle while at the heel the top piece and sides are more nearly in the same plane.

65 Preferably pressure will then be applied in the angles between the margin and the body portions to cause the grooves to be transferred from the inside to the outside of the work. This may be done, for instance, by running a pair of rolls along in said 70 angles while pressing them toward each other or the transferring of the grooves may be effected step by step during the sewing operation which follows. During the sewing, members apply pressure in the grooves, 75 if previously formed, and if not they progressively transfer the grooves from the inside to the outside and securely hold the parts together at a given point in the grooves. While the members are holding 80 the upper clamped at a given point a stitch is formed to secure the body portions together. The members are then released and the work fed the length of the stitch, whereupon the members again hold the work and 85 another stitch is formed. The sewing is preferably done by a curved needle which passes in at the base of one groove and out at the base of another, the stitches appearing on the body portion adjacent to the 90 groove and being invisible on the inner side of the work. The feeding of the work between the stitches is preferably effected by intermittently moving the presser members 95 the length of a stitch in the direction of the seam. After the sewing operation the margins are trimmed away along a line located at the narrowest part of the substance be-

tween the grooves. The portion projecting beyond the general surface of the body portions will then be rubbed down to close the edges together and produce a flat seam and 5 a finished appearance.

In another aspect the method consists in upturning the marginal portions of the pieces, laying the marginal portions against each other, holding the pieces clamped with 10 their edge faces flush and uniting the pieces by a seam the thread of which passes from a point adjacent to the angle of one part through the body portion of that part, through the meeting surfaces of the parts, 15 through the body portion of the other part, and out to the surface of the other part adjacent to the angle of that part.

The thread of the seam thus formed is substantially invisible on the inner side of 20 the work, being embedded for the most part including the lock of the stitch, if a lock-stitch is used, in the body portion and appearing on the outer face of the welt in two lines running parallel with the meeting surfaces of the parts. It will be seen that the seam passes below the engaging surfaces of 25 the margin, so that the thread tension draws the surfaces together into close relation, and that the seam is formed below the plane of 30 the upper or outer surfaces of the two parts of the material and also below the portion clamped or gripped substantially without emerging from the inner surfaces of the parts.

35 In the drawings,

Fig. 1 is a view showing the operation of forming the groove in one of the pieces to be united;

Fig. 2 is a view showing the margins of 40 the two grooved parts temporarily secured together;

Fig. 3 is a view showing one method of transferring the grooves from the inside to the outside of the work;

45 Fig. 4 is a view showing the members for clamping the work in the grooves and for holding and feeding the work;

Fig. 5 is a view similar to Fig. 4 showing the clamping members in clamping position 50 and the needle about to form a stitch;

Fig. 6 is a view showing the parts as they appear after being united by a seam;

Fig. 7 illustrates the operation of trimming away the excess portion of the margins;

Fig. 8 illustrates the operation of rubbing down the seam; and

Fig. 9 is a view showing a portion of a moccasin sewed by the practice of the 60 method of the present invention.

In the practice of the method of the present invention the parts to be united by a seam are first prepared and shaped. If, for example, the method is to be used in

sewing moccasins, the part 2 (Fig. 9) which forms the bottom and sides of the moccasin is first molded or otherwise shaped to correspond to the side and bottom portions of the last and a toe piece 4 of suitable shape is prepared which is slightly larger than is 65 actually required. A top piece 6 will also be cut in the usual manner with a slight excess along its lower edge. The side and bottom portion 2, during the shaping operation to which it is subjected, will usually be stretched enough to provide the excess margin. The edges of the parts to be united are trimmed even and are grooved, preferably on their inner faces, at a predetermined distance from their edges by a knife 8 in the manner shown in Fig. 1, the grooves representing approximately the location of the seam. The parts are then brought together with the groove 10 in one part facing the groove 12 in the other part (Fig. 2) and the margins are then preferably temporarily secured together, for instance, by light wire staples 14.

In the case of a moccasin, the parts are thus held together in proper relation and may be supported on a last which they will fit rather loosely because the temporary fastenings 14 are outside of the line where the stitches are to be made. In placing the parts, which may now be referred to collectively as the shoe, upon the last, the body portion of the side 2 and the body portion of the top piece 6 will be brought substantially into the same plane, their respective margins 16, 18 being at substantially right angles to the body portions and the bends occurring at the weakened portion or line formed by the grooves 10, 12.

At the toe the angle between the side portion 2 and the top portion 4 may approximate a right angle although the side portions may extend sufficiently over the toe to bring the body portions of the parts substantially in the same plane. Either before or after the shoe is placed upon a last the step of transferring the grooves from the inside to the outside of the work may be performed. As shown in Fig. 3, this may be done by running the parts between a pair of pressure rolls

20, 22 which press upon the opposite faces 105 of the work at the line between the margin and the body portion that is at the weakened line formed by the grooves 10, 12. The periphery of the rolls is formed to a shape corresponding to a cross-section of the grooves

and their action results in transferring the grooves from the inside to the outside of the work. In this way the grooves formed on the flesh side of the leather are transferred to the grain side while at the same time the surface of the leather of the grain side is left intact. The use of a roll may, however, be omitted, the step of transferring

115

120

125

the grooves or forming a groove in the grain side, while leaving the grain surface intact, being left to be performed step by step in conjunction with the operation of forming the seam.

As shown in Fig. 4, pressing members 30, 32 have their ends formed to correspond to the shape of the grooves already formed by the rolls or left to be formed by the members. These members 30, 32 are operated relatively to seize the stock which, of course, results in transferring the grooves at a given point from the inside to the outside of the work if they have not already been transferred. With the parts thus held (Fig. 5) a needle 36 enters at 38 near the edge of one groove and, following the dotted line, emerges at 40 near the edge of the other groove. The needle then withdraws and the members 30, 32 are moved to feed the work. Preferably, however, the members 30, 32 are released and moved away from the needle while the needle is in the work, then grip to hold the work while the needle is withdrawn, and then move to feed the work toward the needle and hold the work clamped adjacent to the needle during the passage of the needle into the work.

After the seam has been sewed, which, in the case of the moccasin, is a continuous one extending entirely around the peripheral edge of the portion 2, the margins are trimmed off. This, as shown in Fig. 7, may be done with a blade 42 which preferably has a V-shaped cutting end. The trimming cut is made through the narrowest portion of the substance between the grooves and the elevated portion at the juncture of the two parts is preferably rubbed substantially flat by a tool such as shown at 44 which closes the joint between the parts and finishes the raw surfaces left by the trimming knife. The result is a close, flat seam, as shown by Fig. 9, having the appearance and all the desirable qualities of the best hand work and being in some respects superior.

It will be apparent that the utilization of the method in certain of its aspects does not require the parts to be provided with grooved margins and that the marginal portions may be simply upturned to provide surfaces which may be brought together. These upturned margins are brought together by pressure members such as 30, 32, and since the stitch is formed below the line of initial contact, and, in fact, near the last supported surfaces of the body portion, the tightening of the stitch will draw the parts together and cause contact of the margins of the body portions so that they will be united with a tight joint, the stitches being substantially hidden in the work except along lines parallel to the joint along the outer face of the work.

Having thus described my invention, what

I claim as new and desire to secure by Letters Patent of the United States is:

1. That improvement in methods of uniting leather parts which consists in grooving the parts, placing the parts face to face with the grooves parallel and opposite, holding the parts by pressure applied at the grooves, uniting the parts by stitches, and trimming away the excess of material outside of the stitches. 70

2. That improvement in methods of uniting the edges of leather parts which consists in forming grooves in one side of each part adjacent to the sewing line, disposing the parts with the grooves parallel and opposite, securing the parts together outside the grooves, then securing the body portions together inside the grooves, and trimming away the portions secured together outside the grooves. 80

3. That improvement in methods of uniting the edges of shoe parts which consists in grooving the parts, disposing the parts with their grooved sides in contact, securing the margins together, disposing the body portions of the parts at an angle to each other, pressing the parts together by pressure applied to the outside of the margins opposite to the grooves, securing the parts by stitches to the body portions adjacent to the grooves, and trimming away the margins outside the stitches. 90

4. That improvement in methods of uniting the marginal portions of leather parts which consists in grooving the marginal portions of the parts near their edges, placing the margins together with the grooves facing each other, holding the parts together by pressure on the outside opposite to the grooves, and securing the parts by fastenings extending from a point adjacent to the groove in one part to a point adjacent to the groove in the other part. 100

5. That improvement in methods of uniting the edge portions of leather shoe parts which consists in grooving the edge portions of the parts near their edges, applying pressure in the grooves to hold the parts together, and stitching the parts together by stitches located in the body portions of the parts. 110

6. That improvement in methods of uniting leather parts which consists in grooving the parts, placing the parts face to face with the grooves parallel and opposite, holding the parts by pressure applied at the grooves, uniting the parts by stitches located beyond the grooves toward the body portions of the parts, and trimming away the excess portion outside of the stitches. 120

7. That improvement in methods of uniting the edges of leather parts which consists in preparing the parts, forming grooves in one side of each part at a short distance from its edge, disposing the parts with the

- grooves parallel and opposite, temporarily securing portions of the margins together, then securing the body portions together inside the grooves while using the margins to hold the work, and then trimming away the marginal portions first secured together. 5
8. That improvement in methods of uniting the edges of shoe parts which consists in grooving the parts, disposing the parts with their grooved sides in contact, securing the margins together, disposing the body portions of the parts at an angle to each other, pressing the parts together by pressure applied to the outside of the margins 10
- 15 opposite to the grooves, securing the parts by stitches in the body portions adjacent to the grooves while positioning the parts for sewing by holding the margins at the grooves, and trimming away the margins at 20 the grooves.
9. That improvement in methods of uniting the marginal portions of leather parts which consists in grooving the marginal portions of the parts at a predetermined distance from their edges, placing the margins together with the grooves facing each other, temporarily securing the margins together outside the grooves, holding the parts together by pressure on the outside opposite 25 to the grooves and securing the parts permanently by fastenings extending from a point adjacent to the groove in one part to a point adjacent to the groove in the other part, and then trimming away the temporarily secured margin. 30
10. That improvement in methods of uniting the edge portions of leather shoe parts which consists in grooving the edge portions of the parts at a predetermined distance from their edges, temporarily securing the edge portions together, disposing the body portions of the parts at an angle to each other, applying pressure in the grooves to hold the parts together, stitching the parts 40 together by stitches entering toward the body of the part from one groove and emerging toward the body of the part from the other groove, and trimming away the margins beyond the stitches including the temporary fastenings. 50
11. That improvement in methods of uniting the marginal portions of leather shoe parts which consists in grooving the inner margins of the parts at a predetermined distance from the edges, placing the parts together with the grooves parallel and adjacent to each other, temporarily securing the parts together outside of the grooves, applying pressure from the outside inwardly opposite to the grooves to cause the grooves to be transferred from the inner side to the outside of the work, sewing the parts together by stitches located inside the work relatively to the grooves, and then trimming 55
- away the marginal portion at the narrowest part. 60
12. That improvement in methods of uniting the marginal portions of leather shoe parts which consists in grooving the inner margins of the parts, placing the parts together with the grooves parallel and facing each other, temporarily securing the margins together, transferring the grooves from the inner side to the outside of the work, sewing the parts together by stitches located in the body portions, and then trimming away the temporarily secured marginal portions. 70
13. That improvement in methods of uniting the marginal portions of leather shoe parts which consists in grooving the inner margins of the parts, placing the parts together with the grooves parallel and facing each other, temporarily securing the margins together, transferring the grooves from the inner side to the outside of the work, sewing the parts together by stitches located in the body portions, trimming away the marginal portions, and rubbing down the surfaces formed by the trimming operation. 80
14. That improvement in methods of uniting shoe parts of leather or like material, which consists in bending the margins of the parts at an angle to the body portion, gripping the margins to prevent relative movement, and uniting the parts by stitches formed in the body portions below the upturned margins and arranged to enter and emerge from the material on the same side of the two parts and to be otherwise substantially hidden in said material. 90
15. That improvement in methods of uniting shoe parts which consists in supporting the inner surface of the body portions of the parts in the same plane, upturning the margins at an angle to the body portion, bringing the margins into contact, and securing the body portions together by stitches passing from a face of one body portion through the substance of the body portion to a similar face of the other body portion, all parts of the stitches being outside of the plane of the supported inner surfaces of the body portions. 105
16. That improvement in methods of uniting shoe parts which consists in upturning the margins of the parts to be united and placing the upturned margins in opposition, supporting the inner faces of the body portions, bringing the margins together, passing a needle from the outer surface of one part below the meeting margins to a similar point on the outer surface of the other part, forming and setting a stitch to cause the upturned margins to be secured together, and continuing the stitch forming operation to form a seam between the parts. 115
17. That improvement in methods of 120
- 125

uniting leather parts which consists in forming the parts with upturned margins to be secured in contacting relation, supporting one surface of the body portion of each part, 5 applying pressure to the opposite faces of the body portions adjacent to their margins to hold the margins against each other, and drawing the margins into complete contact-

ing relation by stitches entering the faces of the body portions adjacent to the point to 10 which pressure is applied and lying entirely above the supported faces of the parts.

In testimony whereof I have signed my name to this specification.

FRED N. LA CHAPELLE.
